U.S. PATENT DOCUMENTS

1,631,371 A	6/1927	Greubel
1,671,385 A *	5/1928	Strayer A45C 11/22
		206/811
1,712,109 A	5/1929	Hammer
1,809,696 A	6/1931	Heilweil
1,899,696 A	2/1933	Freedman
1,942,246 A	1/1934	Johaneson
1,986,057 A	1/1935	Hackworth
2,304,528 A	12/1942	Bafia
2,496,296 A	2/1950	Lobl
2,513,575 A	7/1950	Lombard
2,522,480 A	9/1950	Davis
2,672,232 A	3/1954	Kessell, Jr.
3,455,359 A	7/1969	Schweizer
3,716,091 A	2/1973	Gaines
3,749,301 A	7/1973	Peckar
3,831,986 A	8/1974	Kobayashi
3,998,304 A	12/1976	Edgerton, Jr. et al.

FIG. 1 is a front perspective view of a bag showing my new design;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is a front perspective view thereof shown in a closed configuration.

The uneven-length broken lines represent unclaimed boundaries of the claimed design, and the even-length broken lines immediately adjacent to the shaded area represent unclaimed boundaries of the design. The even-length broken lines showing the remainder of the bag represents unclaimed subject matter and form no part of the claimed design.
